CONSOLE PHONOGRAPH OR SIMILAR ARTICLE

Francis W. Campbell, Liverpool, N.Y., assignor to General Electric Company, a corporation of New York

Filed Jan. 17, 1966, Ser. No. 629

Term of patent 14 years

(Cl. D56—4)

Fig. 1.

Fig. 2.

Fig. 3.

FIGURE 1 is a perspective view of a console phonograph or similar article embodying my new design, with the central top cover in a closed position;

FIGURE 2 is a plan view of the console phonograph or similar article as shown in FIGURE 1;

FIGURE 3 is a right end view of the console phonograph or similar article as shown in FIGURE 1;

FIGURE 3 is a right end view of the console phonograph or similar article as shown in FIGURE 1;

FIGURE 4 is a perspective view similar to FIGURE 1, with the central top cover in an open position; and

FIGURE 5 is a front elevation view of the console phonograph or similar article as shown in FIGURE 1.

The dominant features of my new design are shown in solid lines in the drawing, the broken line fragmentary showing of conventional radio and phonograph mechanism in FIG. 4 being for illustrative purposes only.

I claim:

The ornamental design for a console phonograph or similar article, substantially as shown and described.
